United States Patent Office.

EDWIN L. ABERCROMBIE, OF FLORENCE, MASSACHUSETTS.

Letters Patent No. 102,075, dated April 19, 1870.

IMPROVEMENT IN TOOL-HANDLES.

The Schedule referred to in these Letters Patent and making part of the same.

To all whom it may concern:

Be it known that I, EDWIN L. ABERCROMBIE, of Florence, in the county of Hampshire, and State of Massachusetts, have invented a new and useful Improvement in Tools; and I do hereby declare that the following is a full, clear, and exact description thereof, reference being had to the accompanying drawings making a part of this specification, and to the letters of reference marked thereon.

My invention relates to the manufacture of hand-tools used in mechanical labor, such as the adze, axe, railroad-spike hammer and claw, &c., and also those used in agriculture and mining, such as the shovel, spade, pick, hoe, bush-cutter, and many others of that class; and

It consists of a head or holder having a suitable socket to receive the handle, and also other suitable sockets in which to secure the different tools by means of the shanks made thereon in connection with a key or wedge.

In the drawings—

Figure 1 is a longitudinal section of the head or holder, having secured thereon an axe and a pick;

Figure 2 shows a spade having a shank made to fit the longitudinal socket made in the same holder;

Figure 3 is a front view of an adze having a shank to fit its socket in the same head.

Figure 4 is a side view of the same shank;

Figure 5 is a longitudinal section of the same holder, having a pinch-bar therein;

Figure 6 is a front and side view of a claw for drawing spikes;

Figure 7 is a side view of a bush-cutter, having a shank adapted to the same holder; and

Figure 8 is a longitudinal section of the holder.

That others skilled in the art may be able to make and use my invention, I will proceed to describe its construction and the mode of its operation.

In fig. 1, A represents the axe, having the shank b, upon the end of which is the projection a.

D represents the head or holder, which is made of suitable metal, and having a socket, d, therein for the reception of the handle, said socket being somewhat larger in diameter at the inner end than at the outer end.

Extending transversely through the head or part D, is a rectangular socket, b', as shown in fig. 8, and into this socket is inserted the shank b, the projection a extending up into the longitudinal socket or space c, the said shank b being of a size to fit properly the said socket b'.

Any two of the tools having the shank b and projection a thereon may be inserted in the socket b', one

from each side, and the wedge or key C is then forced in tightly, and the tools are secured firmly in the holder, as shown in fig. 1.

Some tools, such as the spade, shovel, pinch-bar, claw, hoe, and some others, may have a straight rectangular shank, c', of a size to fit properly the socket c, and have a hole, e, or a slot therein, so that when the said shank c' is inserted into the socket c, a pin or key may be inserted in the said bar or slot, and shall have a bearing against the shoulder or part x, and they may thus be securely held in place.

To secure the handle firmly in place in the socket d it is only necessary to split the end of the handle slightly, and just insert a wedge, leaving it projecting out from the handle somewhat, and then, the end of the handle being of a size to just fit closely the outer end of the socket d, the handle is driven in smartly, and, the outer end of the wedge being driven down against the inner end of the socket d, the wedge is forced into the handle, which causes the handle to spread laterally and fill the socket d, which being largest at the inner end, prevents the handle from becoming loose in its socket. After the handle is secured in the socket, I am enabled by my improvement to use almost any kind of tool in the holder, changing or removing them at pleasure.

If desirable, I can use only one tool in the holder by using in connection with it a shank having no tool thereon, merely using the simple shank for the purpose of filling out the socket b'. This would be an advantage in performing many kinds of labor, such as mining, when one pick might be used while the other was being sharpened.

A recess is formed in the head D at c", in which the end of the straight shank c' has its bearing to keep it firm when secured in place in the holder D; but this recess c" is not essential when it is desired to use tools having the shank b' thereon, and a holder might be made to accommodate tools having the shank b', leaving out the recess c" altogether.

Having thus described my invention,

What I claim as new, and desire to secure by Letters Patent, is—

1. The shank b, having the projection a thereon, in combination with the holder D and wedge or key C, substantially as described.

2. The improved tool-holder D, when constructed substantially as herein shown and described.

EDWIN L. ABERCROMBIE.
